SPINNING FRAME

Walter S. Eastman, Glendale, R. I., assignor to
Stillwater Worsted Mills, a corporation of
Rhode Island

Application June 4, 1940, Serial No. 338,792

19 Claims. (Cl. 19—136)

My invention relates to spinning frames. It has among its objects to provide an improved pressure mechanism therefor of the type wherein the twisting function is divorced from the drafting function. A further object is to provide such a mechanism wherein the pressure means of this pressure mechanism is both mounted in an improved manner and adapted to cooperate with the top front roll in an improved manner whereby breakage of the yarn is reduced and the work of the operator further facilitated. Further objects of my invention are to provide such improved mechanism of the individually mounted type having an individual pressure roll presenting an exposed end and also such a mechanism wherein this roll is mounted in such an improved manner on the usual lateral extension on its swinging frame as to enable the pressure means to cooperate in an improved and uniform manner throughout its length with the top front roll, while also being automatically retained on its support without requiring special stop means. A still further object of my invention is to provide improved mounting means for the pressure roll carried on the front end of the swinging carrying frame therefor and including improved roll carrying, pivoting, and adjusting means. These and other objects and advantages of my invention will, however, hereinafter more fully appear.

In the accompanying drawing, I have shown for purposes of illustration one embodiment which my invention may assume in practice.

In the drawing:

Figure 1 is an end elevation of a spinning frame equipped with my improvement;

Fig. 2 is a partial front elevation of the spinning frame so equipped;

Fig. 3 is a sectional view on line 3—3 of Figure 1;

Fig. 4 is a perspective view showing a roll supporting structure on the front end of the swinging frame, the roll being shown in spaced relation thereto;

Fig. 5 is an enlarged detail of the pressure roll and its mounting;

Fig. 6 is a sectional view on line 6—6 of Figure 5, and

Fig. 7 is a sectional view on line 7—7 of Figure 6.

In this illustrative construction, I have shown a spinning frame of standard construction including drafting mechanism having a usual carriage stand 1 and suitable drafting mechanism thereon including usual front lower fluted rolls 55

2 and cooperating cork covered top front rolls 3, as well as usual closed pigtail guides 4 above usual whirled bobbins 5 disposed under usual caps 6; my improvements herein relating to improved mounting means, hereinafter described, for the pressure rolls 7 carried on the swinging pressure frame 8 pivoted in a usual manner on the front saddle bar of the stand 1.

In my improved construction, it will be noted that the frame 8, instead of being provided as heretofore with an integral lateral extension on its front end on which the pressure roll is merely rotatably mounted, herein has improved roll carrying means at its front end. More particularly, herein an upstanding block 9 is suitably threaded on a longitudinally extending front threaded portion 10 on the frame 8 and positioned thereon by a suitable lock nut 11. Herein, this block 9 also has an arm 12 fixed in the top thereof and projecting laterally from one side thereof as shown in Figure 5, and also canted slightly forward with respect to the block as shown in Figure 7. Pivoted on this arm 12 is also a roll journaling and supporting sleeve 13 of substantially the width of the roll 7 and received in an enlarged axial bore 14 in the latter and relative to which the roll is freely rotatable. As shown in Figure 6, a pivot pin 15 also extends transversely through the arm 12 intermediate its ends and through spaced washers 16 within the sleeve 13 and shaped to conform to the inner periphery thereof and disposed on opposite sides of the arm 12, while the ends of the pin 15 are riveted in suitable countersinks 35 in the periphery of the sleeve 13.

In the use of my improved construction, it will be apparent that, while carried on the canted arm 12, the roll 7, by reason of the floating mounting or swiveling of the sleeve 13, can conform to the surface of the roll 3, as desired, in such manner as to provide the desired full length contact, and resultant uniform pressure on the yarn, between these rolls. Further, due to the slight forward canting of the pin 12, it will be observed that the effect of the rotation of the roll 3 is such as to cause the roll 7 to be retained on its arm or stud 12 as the rolls rotate together. It will also be apparent that through the adjustment provided between the threaded block 9 and the threaded end 10 of the swinging frame 8, it is possible to adjust the sleeve 13 and roll 7 as desired relative to the roll 3 and frame 8, while the nut 11 retains the parts in any desired position of adjustment.

As a result of my improvements, it is possible

not only to obtain the above advantages, but also materially to reduce yarn breakage while retaining the essential advantages of a pressure means of this type. Further, the work of the operator and replacement of the rolls is facilitated, any need for cotter pin or other connections on the lateral extension at the free end of the roll 7 being eliminated and the latter being readily and quickly slipped on and off the sleeve 13 whenever the frame 8 is depressed. Further, it will be noted that as a result of this construction, the roll 7 while preferably formed of hard wood is also of such form as to be adapted to be inexpensively supplied when formed of other materials having a coefficient of friction adapted to cooperate with the cork covered roll 3. Attention is also directed to the fact that the block 9 and connected sleeve 13 also form a unit adapted to be readily replaced without change in the frame 8 carrying the same. These and other advantages of my improvement will, however, be apparent to those skilled in the art.

While I have in this application specifically described one embodiment which my invention may assume in practice, it will be understood that the same is shown for purposes of illustration, and that the invention may be modified and embodied in various other forms without departing from its spirit or the scope of the appended claims.

What I claim as new and desire to secure by Letters Patent is:

1. In a spinning frame, cooperating front drafting rolls, pressure mechanism including a movable support biased to operative position and pressure means thereon acting on the yarn after it passes out of contact with the lower front roll, and a floating mounting between said support and pressure means.

2. In a spinning frame, cooperating front drafting rolls, pressure mechanism including a movable support biased to operative position and pressure means thereon for pressing the yarn against the top front roll, and a swivel between said pressure means and said support for enabling the surface of said pressure means to conform throughout its length to the surface of said front roll.

3. In a spinning frame, cooperating front drafting rolls, pressure mechanism including a movable support and pressure means thereon for pressing the yarn against the top front roll, and means for enabling said pressure means to conform to said top front roll including a swivel connection between said pressure means and said support.

4. In a spinning frame, cooperating front drafting rolls, pressure mechanism including a movable support and pressure means thereon for pressing the yarn against the top front roll, and means for enabling said pressure means to exert a uniform pressure on the yarn including a swivel connection between said pressure means and said support and spaced longitudinally between the ends of said pressure means.

5. In a spinning frame, cooperating front drafting rolls, pressure mechanism for pressing the yarn against the top front roll including pressure means located in front of the nip of said front rolls and a swinging mount having a lateral extension thereon on which said pressure means is carried, and means for enabling said pressure means to engage throughout its length with said top front roll including a pivotal con-

nnection between said pressure means and said lateral extension.

6. In a spinning frame, cooperating front rolls, pressure mechanism for pressing the yarn against the top front roll including pressure means located in front of the nip of said front rolls and a swinging mount having a lateral extension thereon on which said pressure means is carried, and means for enabling said pressure means to engage throughout its length with said top front roll including a pivotal connection between said pressure means and said lateral extension and spaced longitudinally between the ends of said pressure means.

7. In a spinning frame, drafting mechanism including cooperating front rolls, a movable pressure frame having a front lateral extension, and pressure means pivotally mounted on said lateral extension for pressing the yarn against the top front roll.

8. In a spinning frame, drafting mechanism including cooperating front rolls, pressure means for pressing the yarn against the top front roll, a pressure frame biased to operative position and having a front lateral extension, and a floating mounting for said pressure means on said lateral extension for enabling said pressure means to conform to said roll.

9. In a spinning frame, drafting mechanism including cooperating front rolls, a movable pressure frame having a front lateral extension, and pressure means pivotally mounted on said lateral extension for pressing the yarn against the top front roll including a roll carrying sleeve pivoted on said extension.

10. In a spinning frame, drafting mechanism including cooperating front rolls, a movable pressure frame having a front lateral extension, and pressure means pivotally mounted on said lateral extension for pressing the yarn against the top front roll including a roll carrying sleeve pivoted on said extension on an axis extending transversely relative to said extension.

11. In a spinning frame, drafting mechanism including cooperating front rolls, a movable pressure frame having a front lateral extension, and pressure means pivotally mounted on said lateral extension for pressing the yarn against the top front roll, and means for longitudinally adjusting said front lateral connection bodily relative to said frame.

12. In a spinning frame, drafting mechanism including cooperating front rolls, a movable pressure frame having a front lateral extension canted slightly forward with respect to said frame, and pressure means pivotally mounted on said canted extension.

13. In a spinning frame, drafting mechanism including cooperating front rolls, a movable pressure frame having a front lateral extension canted slightly forward with respect to said frame, a sleeve pivotally mounted on said canted extension, and a pressure roll carried on said sleeve.

14. In a spinning frame, drafting mechanism including cooperating front rolls, a movable pressure frame having a front lateral extension canted slightly forward with respect to said frame, a sleeve pivotally mounted on said canted extension, and a pressure roll carried on said sleeve, said pivot axis being disposed transversely of said extension.

15. In a spinning frame, drafting mechanism including cooperating front rolls, a movable pressure frame having a front lateral extension, a

pressure roll rotatably mounted on said extension, and means between said extension and roll for enabling the latter to engage throughout its length with the top front roll.

16. In an attachment for spinning frames having front drafting rolls, pressure mechanism including a frame biased into operative position, pressure means for pressing the yarn against the top front roll, and a floating mounting between said frame and said pressure means for enabling the latter to conform to such a roll.

17. In an attachment for spinning frames having front drafting rolls, pressure mechanism including a swinging lateral extension, pressure means carried by said lateral extension and engageable with the top front roll, and a pivotal connection between said pressure means and said lateral extension.

18. In an attachment for spinning frames having front drafting rolls, pressure mechanism including a swinging pressure frame having a lateral extension canted slightly with respect to said frame, and a pressure means pivotally mounted on said extension and engageable with the top front roll.

19. In an attachment for spinning frames having front drafting rolls, pressure mechanism including a swinging pressure frame having a lateral extension, a pivotally connected sleeve carried on said extension, and a roll rotatable on said sleeve and engageable with said top front roll.

15
